UNITED STATES PATENT OFFICE.

GEORGE LASKER, OF CHICAGO, ILLINOIS.

BOILER.

Application filed August 12, 1922. Serial No. 561,520.

My invention relates to boilers, and more particularly to means for forcing the fluid passing therethrough into more intimate contact with the heating surfaces and increasing the heating effect.

The invention has among its other objects the production of a device of the kind described which is simple, convenient, compact, durable, reliable, efficient and satisfactory for use wherever found applicable.

Another object of my invention is to provide means in the tubular passages of a boiler for spirally directing the passage of the fluid therethrough, or, in other words, imparting a swirling movement thereto, which means are also adapted to be moved longitudinally within the passages so as to frictionally engage the bounding walls of the passages and remove any scale and soot or other foreign matter adhering thereto.

Many other objects and advantages of the construction herein shown and described will be obvious to those skilled in the art from the disclosures herein given.

To this end my invention consists in the novel construction, arrangement and combination of parts herein shown and described, and more particularly pointed out in the claim.

In the drawings, wherein like reference characters indicate like or corresponding parts,

Figure 1 is a side elevation of a boiler showing one of the fluid-directing vanes in place;

Figure 2 is an enlarged fragmentary elevation of the same;

Figure 3 is a section substantially on the line 3—3 of Figure 2;

Figure 4 is a fragmentary section through a water tube boiler showing the fluid-directing means as arranged within the water tubes;

Figure 5 is an enlarged detail of the fluid-directing means in place in one of the tubes.

In the drawings, wherein I have illustrated a preferred embodiment of my invention, 1 indicates a boiler of any preferred design, shape and material having a plurality of flues 2 arranged longitudinally thereof and through which the heating medium must pass in order to contact with the water contained in the drum. Removably positioned in one or more of the flues, and preferably in each of them, are cores or vanes 3 for directing the heating medium

in a predetermined path, said fluid-directing means in this particular instance comprises a longitudinally-extending bar of S-shaped cross-section, as shown most clearly in Figure 3, and of a width substantially equal to the inner diameter of the flue, so as to frictionally contact with the inner wall thereof when inserted therein.

The member 3 is twisted spirally along its length, as shown, so that the sides thereof engage the inner wall of the flue along spiral lines. Thus it will be apparent that any of the heating fluid passing through said passages or flues will be directed in spiral paths longitudinally of the flues, and thus will not only increase the velocity of the fluid, but will force it into more intimate heating contact with the surrounding portions of the water drum, thus increasing the efficiency thereof. As before noted, the member 3 may be movable longitudinally of the tube, so that any soot or other foreign matter adhering to the inner surface of the flue will be removed therefrom whenever said member 3 is reciprocated within the flue.

An opening 4 may be provided at one or both ends of the member 3, so as to assist in drawing said member into the flue by means of a cable or the like, or in engaging it by any suitable cooperating means for reciprocating it during its cleaning action.

In the modification shown in Figures 4 and 5, the member 3 is positioned centrally within and extending longitudinally of the steam tubes 5 of a water tube boiler 1', so as to impart a spiral or whirling movement of the steam passing through said tubes, thus forcing it into a more intimate contact with the heated tubes, preventing the burning of said tubes and increasing the heating effect.

It is to be understood that the member 3 may be made rigid or flexible simply by varying the gauge of the material used. If the member 3 is of sufficiently light gauge and flexible, it may be moved lengthwise of the steam tubes 5 shown in Figures 4 and 5, in the same manner as they are moved longitudinally of the flues 2 shown in Figures 1, 2 and 3, for the purpose of removing the scale or other foreign matter adhering to the inner surface of the water tubes.

Having thus described my invention, it is obvious that various immaterial modifications may be made in the same without departing from the spirit of my invention;

hence I do not wish to be understood as limiting myself to the exact form, construction, arrangement, and combination of parts herein shown and described or uses mentioned.

5 What I claim as new and desire to secure by Letters Patent is:

In combination, a boiler having a plural-
ity of tubes therethrough for the passage of
fluid, and core members arranged within the

10 tubes and engaging the inner faces of the

walls of the tubes, said core members each
consisting of a strip which in cross section is
formed S-shaped and tapering from its cen-
tral part to its side edges, and said strip be-
ing twisted lengthwise thereof to extend 15
in spiral formation.

In testimony whereof I have hereunto
signed my name.

GEORGE LASKER.
